CROSS ROLLER BIT

Nelson B. Berleth, Houston, Tex., assignor to
 Hughes Tool Company, Houston, Tex., a corporation of Texas

Application February 18, 1935, Serial No. 7,027

7 Claims. (Cl. 255—71)

My invention relates to cross roller bits employed in drilling deep wells. The cross roller bit is characterized by a head having mounted at the forward end thereof a set of diametrical cross rollers which cut the center of the hole, and a pair of opposed inclined side cutters to cut the gage of the hole.

It is an object of the invention to provide a drill on which the side cutters are mounted for rotation upon a removable bridge which can be replaced when worn.

I also desire to mount the cross rollers upon a removable and replaceable shaft.

It is the main object of the invention to provide a structure of the character stated in which the cutters and their supports may be replaced when worn without renewing the bit head and in which the parts are rigidly supported and strongly built so that none of the parts may be broken or lost in the hole.

I so construct the head and the cutter supports that they may be secured together in the assembling operation by welding, and so that they may be readily disassembled by use of a cutting torch.

In the drawing herewith, Fig. 1 is a central longitudinal section through a bit head constructed according to my invention.

Fig. 2 is an inner side view taken at right angles to the view seen in Fig. 1 and partly in section through the cross roller cutters.

Fig. 3 is a bottom plan view of the head and cutters.

Fig. 4 is a broken detail in side elevation.

Fig. 5 is a broken view similar to Fig. 2 but showing a slightly different embodiment of the invention.

The invention resides largely in the structural details of a cross roller bit. The head 1 is generally circular in outline. It has an upwardly-tapered, threaded shank 2 for attachment to the drill collar. On the lower end are two opposite legs 3 and two opposite legs 4 set at 90° from the first set of legs 3. These legs enclose a recess or pocket 5 in which the cutters are partially housed.

The drill head is split longitudinally along a plane indicated by the line 6 in Fig. 1. The shank and head are formed with a water course 7 which has branching ducts 8, 8 and 9, 9 discharging upon the cutters. The legs 4 have an inner plane face 10, inclined upwardly and inwardly. Short stub shafts 11 project from the faces 10 at approximately right angles thereto. Between these shafts 11 is a bridge member 12 the ends of which are enlarged and formed with

sockets to engage over the shafts 11. The outer peripheries of the ends of said bridge are cylindrical at 13 to form a race for roller bearings 14 upon which the toothed cutters 15 are rotatable. I prefer to place washers 16 between the cutters 15 and the wall faces 10 to take up the wear. As will be seen, I form a shoulder at 17 on the inner side of the bearing to form a lateral thrust support for the bearings and cutters.

The intermediate portion of the bridge 12 is flattened into a web 18 from which project opposite aligned shafts 19. As will be seen from Fig. 3, the web is set slightly off center so that one shaft 19 is slightly longer than the other and will hence support a longer cross roller cutter 20. The ends of the shafts 19 are adapted to fit within grooves or notches 21 in the legs 3. The lower portion of the notch is then closed with a bond of welding material 22 which when in position closes the lower end of the split 6 in the 20 bit, as will be seen in Fig. 3.

The cross roller cutters 20 are preferably, although not necessarily, tapered from their outer ends inwardly. They have roller bearings 23, shown as set in grooves formed in the cutters. 25

While I may form the shafts 19 integral with the bridge member, as described, I contemplate that the shaft may be made separate and extended through an opening in the bridge member 18' and into openings in the legs 3, said openings 30 being closed below the same as shown at 26. The cross roller cutter shaft is then held securely by a bond of welding material 24 at the ends, as seen in Fig. 5.

When this bit is assembled, the cutters and bearings are fitted in position upon the bridge member and the cross roller shaft. The two halves of the head are then put together with the shafts 11 engaging in the ends of the bridge member. The ends of the shaft 19 will be received in notches 21. The parts of the head are then welded together and the cross roller shaft 19 is welded in place by the weld 22. When the shank 2 is screwed into the drill collar, the head is held together so that there is no danger of the head coming apart in use.

It will be seen that the parts may be quickly disassembled by the use of a torch to cut away the welds. The bit may be easily repaired in the field and new sets of cutters and shafts may be quickly installed. The drill has the further advantage that the cutters are firmly mounted and strongly supported.

What I claim as new is:

1. A cross roller bit including a head, inward-

- ly extending shafts on said head at the forward end thereof, a bridge having sockets fitting over the ends of said shafts, side cutters mounted for rotation on the opposite ends of said bridge, a cross roller shaft transversely of said bridge, supports for the ends of said cross roller shaft and cutters on said cross roller shaft.
5. A cross roller bit including a head, inwardly extending shafts on said head at the forward end thereof, a bridge having sockets fitting over the ends of said shafts, side cutters mounted for rotation on the opposite ends of said bridge, a cross roller shaft transversely of said bridge, and supported on said bridge, said shaft being longer 10 on one side of said bridge than on the other, and cross roller cutters on said cross roller shaft.
6. A cross roller bit including a head, downwardly inclined stub shafts thereon, said head being longitudinally divided and adapted to be held together by welding, water channels longitudinally of said head, a bridge having sockets fitting over the ends of said shafts, side cutters mounted for rotation on the opposite ends of said bridge, across roller shaft transversely of said bridge, supports for the ends of said cross roller shaft and cutters on said cross roller shaft.
7. A drill comprising a head, a recess in the lower end thereof having two opposed upwardly converging walls, inwardly projecting stub shafts 15 on said walls, a supporting bridge extending transversely across said recess, upwardly and outwardly inclined sockets at the ends of said bridge to engage over said stub shafts, bearings on the ends of said bridge, side cutters on said bearings, a cross roller shaft supported by said bridge midway the ends of said bridge, supports in said

head for said cross roller shaft, and cross roller cutters on said cutter shafts.

5. A drill comprising a head, a recess in the lower end thereof having two opposed upwardly converging walls, inwardly projecting stub shafts 5 on said walls, a supporting bridge extending transversely across said recess, sockets formed in the ends of said bridge engaging over the ends of said stub shafts, bearings on said bridge adjacent said shafts, cutters, on said bearings, a 10 cross roller shaft supported by and extending laterally from said bridge and cross roller cutters on said cross roller shaft.

6. A drill comprising a head having a recess in its forward end, opposite downwardly flaring 15 walls in said recess, stub shafts projecting inwardly at approximately right angles to said inclined walls, a bridge extending across said recess and supported at its ends on said shafts, cutters rotatable upon the ends of said bridge, a 20 cross roller shaft supported by and extending laterally from said bridge and cross roller cutters on said cutter shaft.

7. A drill comprising a head having a recess in its forward end, opposite downwardly flaring 25 walls in said recess, stub shafts projecting inwardly at approximately right angles to said inclined walls, a bridge extending across said recess and supported at its ends on said shafts, cutters rotatable upon the ends of said bridge, a cutter 30 shaft extending across said recess approximately at right angles to said bridge, and a cross roller cutter on each end of said cutter shaft, one of said cross roller cutters being longer than the other.

35 NELSON B. BERLETH.
